UMBRELLA ATTACHMENT

Filed April 18, 1929

THEODORE P. GARANKIN
INVENTOR.

BY John P. Nikourov
ATTORNEY

UNITED STATES PATENT OFFICE

THEODORE P. GARANKIN, OF NEW YORK, N. Y.

UMBRELLA ATTACHMENT

Application filed April 18, 1929. Serial No. 356,158.

My invention relates to umbrella attachments and has a particular reference to attachments for operating spring clips controlling open and closed positions of the umbrella.

In an ordinary umbrella the spring latch holding the sliding bushing for the ribs in its extreme position must be depressed by hand in order to release this bushing, which can be then moved to its other extreme position. This method of operating the latch often causes inconveniences, by pinching one's fingers, soiling or pinching gloves etc.

In order to obviate this difficulty I devised a special tube loosely fitted on the sliding bushing for the ribs and completely covering the latch. This tube is pivotally supported on one side and can be rocked between its extreme positions, thereby depressing the latch and releasing the sliding bushing.

My invention is more fully described in the accompanying specification and drawing in which—

Fig. 1 is a side view of my device, Fig. 2 is a section on the line 2—2 (Fig. 1) with the tube in an inoperating position (with the latch released), Fig. 3 is a similar section showing the tube in an operating position with the latch depressed, Fig. 4 is a sectional elevation of my device, Fig. 5 is a section on the line 5—5 (Fig. 1), Fig. 6 is a side view of a modified device, Fig. 7 is a sectional view of a modified device, Fig. 8 is a sectional view for the Fig. 6, taken on the line 8—8, Fig. 9 is a partial sectional view of the sliding bushing with a pivoting lip, Fig. 10 is a partial side view showing the pivotal lip, and Fig. 11 is a sectional view of a modified device.

My attachment consists of a tubular member 1 loosely fitted over a sliding bushing 2 of an umbrella 3. The bushing 2 can be of an ordinary construction with slots on top for the ribs (not shown). It is slidably fitted over the stem of the umbrella and has slots 5 and 6 for spring latches 7 which hold the bushing 2 in its extreme positions at the bottom and top of the umbrella rod (stem).

Two (or more) slots 8 are punched in the wall of the bushing 2, the slots being placed

lengthwise on one side. The punched out portions are bent as shown in Figs. 9 and 10, preferably forming rounded teeth. These teeth form pivots for the sleeve or tubular member 1 which has corresponding slots 55 punched to fit over the teeth 11. The teeth are then bent sideways as shown in Figs. 1, 2 and 3, in order to retain permanently the sleeve 1 which can then rotate or swing around these pivots being of a sufficiently 60 large diameter inside for such movements. Portions of the sleeve adjacent to the bushing 2 are made concentric with this bushing and snugly fit it in the extreme positions of the sleeve. The middle portion of the sleeve, 65 opposite the hinge or pivot 11, is curved so as to provide a bulge or pocket adapted to fit over the spring latch 7 of the umbrella. The hinge 11 is located in such position that the sleeve, being moved or swung to the right 70 (Fig. 2) forces the latch 7 down thereby releasing the bushing 2 to be moved on the umbrella stem (Fig. 3). In the position of the sleeve 2 as shown in Fig. 3, turned to the right, the bulge in the sleeve will clear the 75 upper latch of the umbrella, if the latches are arranged in the usual manner, i. e. at right angles with each other. In order to depress the upper latch the sleeve must be turned to the left in which position it will clear the 80 lower latch when brought in this position down (Fig. 2).

The operation of my device is as follows.

The umbrella is held in left hand by the handle 12 and the sleeve 1 is grasped with the fingers of the right hand. It is then swung or rocked on its hinge so as to depress the latch 7 holding the bushing 2 with umbrella ribs in the lower or inoperating position (umbrella folded). The sleeve 1 is then pushed up on the umbrella stem, retaining the same grip with fingers, until the bushing 1 passes over the upper latch 7 and becomes engaged by the latter, the latch fitting in the bulge of the sleeve. The movements are reversed when it is desired to return the sleeve down and to fold the umbrella.

A shortened sleeve 1 is shown in Fig. 6 and a modified shape in Fig. 7, the latter being provided with ribs or projections 13 in 100

order to provide a better grip for the fingers. The sleeve shown in Fig. 11 has no bulge and is formed specially for a condition when the upper and lower latches are located in the same plane.

Important advantages of my attachment are that it provides a simple and effective means to operate the latches of ordinary umbrellas without any danger of pinching fingers or damaging gloves. The operation is made much easier as the depression of the latch is accomplished by the combination of sliding and pressing movements of the sleeve.

I claim as my invention:

1. In an umbrella attachment, the combination of a tubular member loosely fitted over the sliding bushing of said umbrella, and means to rockingly support said member on said bushing, a portion of said member being in a cooperative relation with a spring latch of said umbrella, said tubular member being adapted to depress said latch of said umbrella when manually operated.

2. In an umbrella attachment, the combination of a tubular member loosely fitted over the sliding rib bushing of said umbrella, a hinge supporting said tubular member on said bushing, a portion of said member being adapted to cover a spring latch of said umbrella, said tubular member being adapted to be manually rocked on said hinge thereby operating said latch of said umbrella.

3. In an umbrella attachment, the combination of a tubular member loosely fitted over the sliding bushing of said umbrella, a hinge supporting one side of said member on said bushing, and a bulged portion on said tubular member adapted to enclose the spring latch of said umbrella, said member being adapted to be manually rocked on said hinge, thereby depressing said latch.

In testimony whereof I affix my signature.
THEODORE P. GARANKIN.
